(57) **CLAIM**

We claim the ornamental design for a strap link, as shown and described.

DESCRIPTION

FIG. 1 is a perspective view of a strap link showing our new design.

FIG. 2 is a first side view of the strap link of FIG. 1.

FIG. 3 is a second side view of the strap link of FIG. 1.

FIG. 4 is a first end view of the strap link of FIG. 1; the opposite end view being a mirror image thereof.

FIG. 5 is a top view of the strap link of FIG. 1; and,

FIG. 6 is a bottom view of the strap link of FIG. 1.

The broken lines in the drawings represent portions of the strap link and form no part of the claimed design. The strap link is shown with a symbolic break in its length indicated by the dot-dashed parallel lines. The appearance of any portion of the strap link between the line breaks forms no part of the claimed design.
